UNITED STATES PATENT OFFICE.

FRANK E. ROSEKELLY, OF HURON, OHIO.

PLOW ATTACHMENT.

Application filed September 13, 1927. Serial No. 219,270.

This invention relates to an attachment for plows, one of the objects being to provide a simple and efficient device which, when applied to the beam of a plow in proper position, will act to gather and turn down the weeds in the path of the plow so as to insure clean plowing.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed, without departing from the spirit of the invention.

In the accompanying drawings, the preferred form of the invention has been shown.

20 In said drawings,

Figure 1 is a side elevation of a plow having the present improvements combined therewith.

25 Figure 2 is a plan view of the structure shown in Figure 1.

Figure 3 is a view partly in plan and partly in section showing the relative position of the jointer and the attachment constituting the present invention, said view being primarily a section on line 3—3, Figure 1.

30 Figure 4 is a section on line 4—4, Figure 2.

Referring to the figures by characters of reference 1 designates the beam of a plow 2 and located adjacent this point of the plow is 35 a jointer 3 following a disk 4. This structure is similar to that of plows already in use.

The attachment constituting the present invention includes a standard 5 the lower end of which has an arm 6 extending at an angle 40 therefrom and curved rearwardly and laterally as shown particularly in Figures 1 and 2. Secured to the side face of the standard 5 and the front face of the arm 6 is a deflecting shield 7 formed of a sheet of relatively 45 stiff material, such as steel, the inner or forward edge of this sheet being bent backwardly as indicated at 8 so as to straddle the standard 5 to which it may be connected by means of rivets 9 or in any other suitable manner. 50 The lower edge of the shield is flush with the lower edge of the arm 6 and is connected to said arm by rivets or the like, as shown. The

shield 7 is so curved that its intermediate and outer end portions are inclined upwardly and forwardly. Consequently, as the plow is 55 moved forwardly, this shield when properly attached to the plow, will gather standing vegetation and deflect it downwardly into the path of the plow so that the soil, when overturned will be deposited on this vegetation. 60 The standard 5 can be attached to the beam 1 in any manner desired. As shown in the drawings it is held to one side of the beam by means of clamping plates 10 connected by bolts 11 extending above and below the beam 65 and at opposite sides of the standard.

It will be noted that this attachment can be applied readily to a plow and it will be found that in practice constitutes very efficient means for dragging the vegetation forwardly 70 into the path of the plow so that it will be covered properly.

The shield can of course be made of any desired number of pieces and of any materials and the means for connecting it to a plow 75 can be varied to meet the conditions under which the shield is to be used.

What is claimed is:

1. An attachment of the class described including a standard, means for securing the 80 same to the beam of a plow, a rearwardly and laterally curved arm at the lower end of the standard, and a plate secured to the standard and the front face of the arm, said plate being curved from side to side with its concave 85 face in front and inclined upwardly and forwardly.

2. The combination with a structure including a jointer and a turning plow, of an attachment including a standard, means for detachably securing the standard to the structure, said standard being supported above the path of the jointer, a rearwardly and laterally curved arm at the lower end of the standard extending across the path of the 95 turning plow, and an upwardly and forwardly inclined plate secured to the standard and arm and curved from side to side, the front face of the plate being concave and constituting means for deflecting vegetation forwardly and downwardly into the path of the plow. 100

In testimony that I claim the foregoing as my own, I have hereto affixed my signature.

FRANK E. ROSEKELLY.
